DESIGN FOR A RAZOR BLADE KNIFE

Frank A. Johnson, San Francisco, Calif.

Application November 20, 1944, Serial No. 116,452

Term of patent 3½ years

(Cl. D22—3)

To all whom it may concern:

Be it known that I, Frank A. Johnson, a citizen of the United States of America, residing at San Francisco, in the county of San Francisco and State of California, have invented a new, original, and ornamental Design for a Razor Blade Knife, of which the following is a specification, reference being had to the accompanying drawing, forming a part thereof.

Fig. 1 is a side elevation of a razor blade knife, showing my new design.

Fig. 2 is a top plan view of the same, and

Fig. 3 is an end view of the same looking from the left of Fig. 1.

I claim:

The ornamental design for a razor blade knife, substantially as shown.

FRANK A. JOHNSON.
